UNITED STATES PATENT OFFICE.

ALBERT GALLATIN SAFFORD, OF BOSTON, MASSACHUSETTS.

SASH FASTENER.

SPECIFICATION forming part of Letters Patent No. 307,805, dated November 11, 1884.

Application filed June 2, 1884. (No model.)

To all whom it may concern:

Be it known that I, ALBERT GALLATIN SAFFORD, of Boston, in the county of Suffolk, of the Commonwealth of Massachusetts, have 5 invented a new and useful Improvement in Window-Sash Supporters or Fasteners; and I do hereby declare the same to be described in the following specification and represented in the accompanying drawings, of which—
10 Figure 1 is a front view, and Fig. 2 a vertical section, of portions of a window frame and sash provided with my invention, the nature of which is defined in the claims herein-after presented. Fig. 3 is a front view, and Fig. 4 an edge view, of the friction-catch or sash-supporter to be described. Fig. 5 is an inner side view of part of the window-frame grooved bar as notched to receive the catch or sash-supporter. Fig. 6 is a front view, Fig. 7 15 an edge view, and Fig. 8 a vertical section, of a portion of the sash-bar, showing its sockets and recesses for receiving the friction-catch or sash-supporter. Figs. 9 and 10 are herein-after described.
20 The said sash-supporter (shown at A) consists not only of an arm or stiff piece of wire, a, having two right-angular bends in it in the same direction, as represented at b and c, but of a spiral spring, s, having one of the parts, 25 d and e, of the wire extended into and through it, the spring at its outer end being inserted into a hole made transversely in the part d. At its other end the spring has its wire extended outwardly from it in manner as shown 30 at f. The vertical bar B of the sash has a socket, g, bored horizontally in it from its outer edge, and of a length somewhat more than sufficient to receive the spring s. There is also in the bar from its outer edge, and extending down from the socket g, a socket, h, to receive the extension f of the spring. Furthermore, there extends upward from the socket g, and in the outer edge of the sash-bar, a 35 groove or recess, i, and there projects from the head or upper part of such recess transversely across the face of the sash-bar another groove or recess, k, such grooves or recesses and sockets being to receive the friction-catch or such sash-supporter arranged in them, as 40 shown, which, when the sash is in the window-frame, projects into the next adjacent sash—
45

receiving groove, l, thereof, the part e of the catch being forced by the spring against one side of the said groove, against which it bears with friction to support the sash when raised 55 in the groove.

In the window-frame, and opening out of the sash-groove at the side thereof against which the catch bears, is a notch or series of notches, m, to receive the upper part, e, of the 60 catch, and with such to operate to lock the sash in position, whether it be wholly down or raised in the window-frame. By pressing against the part e so as to force it back into its groove of the sash-bar, the friction-catch 65 may be thrown out of engagement with the notch, in order to allow of the sash being moved within the window-frame. To aid in effecting such a movement of the sash-supporter, it may have a knob extended from its 70 part e, or, what is better, such may be accomplished by a bent rocker-lever, E, pivoted to the sash-bar, or connected thereto by screws p going through it into the bar loosely, a perspective view of such lever being given in Fig. 75 9, and a top view of it as applied to the sash and catch in Fig. 10. The said lever has one arm lapping on the part e of the supporter. By properly pressing on the upper arm the lever may be rocked so as to cause the catch 80 of the supporter to be moved out of contact with the side of the groove of the window-frame.

Without the notch or notches in the window-frame the friction-catch or sash-supporter answers as a means of holding or sustaining the sash by friction when such sash may be raised in the grooves of the window-frame. My said sash-supporter is specially useful for the windows of railway-cars, though applicable to 85 other windows having a sash or sashes to slide in grooves.

I do not claim a rigid catch consisting of a piece of wire bent five times, in the manner as represented in the United States Patent No. 95 129,149, and arranged in a recess made in a window-frame and held therein by staples, and provided with a spring adapted to its lower part and bearing against the bottom of the recess, the piece of wire of my sash fastener 100 or supporter being bent at a right angle but twice in the same direction, and its spring

encompassing the lower straight part, *d*, so as with it to be inserted in a cavity, *g*, bored in the sash, such cavity being at a right angle to the recess *i*, for receiving the stem or median part of the wire.

It will be perceived that my sash fastener or supporter is applied directly to and moves with the sash, and its part *e* bears against one side of the groove in which the sash runs, such side having in it one or more notches to receive the part *e*, in order to lock the sash in the window-frame.

My sash fastener or supporter, made in the form and applied as described to the sash, so as to be movable therewith, requires no staples to keep it in place in the sash, and may be operated without the rocker-lever adapted to the sash, as in the arrangement of the sash-supporter in sash the part *e* projects from the window-frame and the sash in a manner to enable the finger of a person to be directly applied to such part *e* for moving the sash-supporter. The rocker-lever separate from the sash-supporter and pivoted to the sash is an auxiliary of manifest advantage.

I claim—

1. The sash-bar provided with the transverse and longitudinal recesses, and the two sockets arranged in it as set forth, in combination with the sash-supporter arranged in

such recesses and sockets, and consisting of a wire, *a*, having the two right-angular bends *b* and *c*, and of the spiral spring *s*, provided with the extension *f*, all being essentially and to operate as explained.

2. The window-frame having one notch or a series of notches arranged to open out of one of its sash-grooves at one side thereof, as explained, in combination with the sash provided with the transverse and longitudinal recesses and the two sockets, and with the sash-supporter arranged in such recesses and sockets, and consisting of the wire *a*, having the two right-angular bends, and of the spiral spring *s*, having the extension *f*, all being essentially as set forth.

3. The combination of the rocker-lever, applied to the sash-bar and to the sash-supporter as described, with such bar, recessed and socketed as explained, and with the sash-supporter arranged within the recesses and sockets of the bar, and consisting of the wire *a*, having the two right-angular bends, and of the spring *s*, provided with the extension *f*, and arranged with and fixed to the said supporter as specified.

ALBERT GALLATIN SAFFORD.
